MACHINE FOR HANDLING STRIP MATERIAL

George Schaefer, Jr., Flushing, N. Y., assignor to Sanitary Public Service Corporation, New York, N. Y., a corporation of Delaware

Application December 19, 1933, Serial No. 703,101

22 Claims. (Cl. 242—58)

The present invention relates to machines for handling strip material, and is more especially directed toward web handling mechanism wherein the web of an active web roll is automatically replaced by the web of a reserve web roll upon depletion of the active web roll to a predetermined amount.

Vending and dispensing devices for making and dispensing articles out of a web of paper are generally manually operated and unattended except for ordinary servicing. It has heretofore been customary to supply these devices with a single active roll of paper which must be replaced when it becomes depleted. This replacement was a manual operation not automatic in nature, and to insure against complete exhaustion of supply it was necessary to make the replacement before the active roll was completely exhausted. This required close attention and frequent servicing, and at best it could result only in wastage of material or complete exhaustion of the material from the machine, so that the desired articles could not be obtained.

The present invention contemplates means whereby such a vending or dispensing machine may be provided with two web rolls, one an active web roll which is depleted as the machine is operated, and the other a reserve web roll, identical with the active roll, and associated with suitable mechanism whereby upon depletion of the active roll to a predetermined extent the web of the reserve roll is automatically threaded into the machine so that the articles are then made from the paper or material of the reserve roll.

According to the present invention the feeding in of the reserve web is accomplished mechanically, reliance being placed on a friction seizure rather than the use of adhesives, common in web replenishing mechanism of printing presses, paper bag machinery, and the like.

According to the present invention the active web is threaded through the machine in the customary manner and in the normal operation of the machine its depletion takes place without in any way affecting the reserve web. The end of the reserve web is removably secured to a device which holds it stationary, adjacent the active web and a roller about which the active web is passed. This member is held in this position so long as there is sufficient material on the active roll. But, as soon as the material on the active roll is depleted beyond the predetermined amount, then the member carrying the end of the reserve web is released and automatically carried in between the active web and the cooperating roller,

so that the friction between the parts withdraws the reserve web and threads it through the machine so that two webs are passing through it until the active web is completely exhausted.

According to the present invention the structure is so designed that the roll which has been transferred from being in reserve to being "active" may be manually shifted to the position occupied by the former active roll, without making it necessary to interfere with the threading of the web through the machine. A new reserve roll may then be inserted in place and prepared for automatic substitution.

A further object of the present invention is to provide a mechanism wherein the manual threading of the material through the machine need not be repeated so long as a reserve roll has been kept ready for insertion automatically.

The present invention has been designed particularly for use in connection with vending and dispensing machines for paper towels and toilet seat covers and will be described in connection with such machines. However, it is capable of general application in web handling machines wherein a new web should be substituted upon the exhaustion of the one already in the machine.

Other and further objects will appear as the description proceeds.

The accompanying drawings show, for purposes of illustrating the present invention, two of the many embodiments in which the invention may take form, it being understood that the drawings are illustrative of the invention rather than limiting the same. In these drawings:

Fig. 1 is a front elevational view of one form of a seat cover and towel forming machine supplied with the web replenishing mechanism, the cover of the enclosing casing being open and parts being broken away to show interior construction;

Fig. 2 is a sectional view on the line 2—2 of Fig. 1, the casing being closed, showing the right frame and parts carried thereby in elevation;

Fig. 3 is a sectional view taken on the line 3—3 of Fig. 1; the full lines indicating the parts in the normal or reserve position, the dot and dash lines indicating the parts in position after the exhaustion of the active web and the drawing in of the reserve web;

Fig. 4 is an enlarged sectional view of a fragment of Fig. 3, the full lines indicating the position of the parts just before the reserve web is drawn into the machine; and

Fig. 5 is an elevational view of a modified form

of construction, parts being broken away and parts in section.

In Figs. 1-4, inclusive, of the drawings, the machine is shown as mounted in an enclosing 5 casing or housing. It has a fixed back wall 10, side walls 11, 12, bottom wall 13, and a cover or front case 14 hingedly secured at 15 to the side walls 11 and 12.

The side frames of the machine are indicated 10 at 29 and 21. While these side frames may be made of castings, they are preferably made, as here shown, in the form of a sheet metal stamping having stiffening flanges as indicated at 20a and 21a. The rear edges of these side frames 15 are bent laterally to provide mounting flanges indicated at 20b and 21b, which extend from the top to the bottom of the frame. The side frames are secured together by upper and lower cross members 22 and 23. These may also be formed 20 of sheet metal and welded to the side frames 20 and 21. A lower front tie rod is indicated at 24. The frame and case are secured together by screws 24' passing through slots 24''. The side frames 20 and 21 carry side plates 25 and 26, 25 which are secured in place by screws indicated at 27, Fig. 2.

A female roll is indicated at 28. It is provided with a series of grooves indicated at 28a, 28b, 28c, 28d, to cooperate with knives, carried by 30 a male roll to be described, for the purpose of forming the toilet seat cover or towel. This female roll is mounted on a shaft indicated at 29 and is keyed to the inner end 30 of a crank indicated at 31.

The crank 31 also drives two gears, indicated at 32 and 33. The gear 33 is in mesh with an idler gear 34 pivoted at 35 on the side plate 25. The idler gear 34 meshes with another idler gear 36 pivoted at 37 on the side plate 25. Backward 40 turning is prevented by a pawl indicated at 36'. The idler gear 36 meshes with a gear 38 pivoted on a shaft indicated at 39 and supported at the lower end of hangers 40 and 41. The hangers are pivoted on studs 40a and 41a. The shaft 39 45 carries a cutter drum indicated at 42 which is provided with knives indicated at 43 and 44 co-operable with the grooves in the female roll 28 for forming seat covers and/or towels.

A stop lever 45 is pivoted at 46 to the side frame 50. A spring 47 presses the shoulder 48 downwardly to enter behind a shoulder 49 carried by a disc 50 secured to the crank 31.

A selector lever 51 is loosely pivoted about the crank shaft and is biased to the position indicated 55 in the drawings by a spring 52. The selector lever 51 has a notch 53 to receive the nose 54 of the stop lever 45 and irrespective of whether the selector lever 51 is raised or lowered, the nose of the stop lever 45 is lifted upwardly to carry the 60 shoulder 48 above the edge of a cam plate 55 urged to the right by a spring 56. This cam plate is loosely carried on the crank shaft and is secured to the cam 50 by a screw 57 passing through a slot 58.

The selector lever 51 is provided with a rearward extension 59 adapted to engage the front end of a latch lever 60 pivoted on a shaft 61 mounted in the side frames of the machine. A similar latch lever 62 is carried outside the left 70 side frame. These two latch levers cooperate with lugs 63 and 64 carried by the hanger arms 40 and 41, and are held against these lugs by a spring indicated at 65. When the front end of the selector lever is lowered, the rear end is raised 75 and brought against the latch lever 61, which

brings the latch levers above the lugs so that springs, one of which is indicated at 67, will pull the male cutter cylinder rearwardly. This separates the male and female rolls so that the cutter blades 44, designed for making the flap of the toilet seat cover, do not reach the grooves in the female cylinder.

Mechanism not shown herein but shown and described in detail in my application executed concurrently herewith, for Dual purpose seat 10 cover and towel forming machines, Serial No. 703,100, filed December 19, 1933, is employed to restore the cutter drum and hangers to the position shown in the present drawings, so that the cut-off knife 43 may cooperate with the groove 15 28a in the female roll to sever the paper.

An active web roll is indicated at W. In the present type of machine it consists of a roll of paper toweling of sufficient width to form a seat cover and soft enough to be readily disposed of. 20 This active roll W is wound about a core indicated at 70, and this core is mounted in core ends or roll holders 71 adapted to be received in bearing members 72, secured to the side frames 20 and 21. Arms 73 and 74 are pivoted to the frames 25 as indicated and are provided with friction shoes 75 which are pressed against the paper roll ends by springs as indicated at 76.

The web w from the active roll W is passed about a guide roll 77 pivoted to the side plates 30 25 and 26 and thereby applied to the surface of the female roller 28 near the top of this roller. The active web passes about this roller 28 and between the roller 28 and a number of toothed rubber rollers indicated at 78, Fig. 1. These 35 rubber rollers are mounted on a shaft 79 driven by a gear, indicated at 80, which meshes with the gear 32 carried by the crank shaft. The toothed rubber rollers press against the female roller 28 and the two together act as drawing rollers to 40 draw the web through the machine. The web w, after passing between the knives and the drawing rollers, is delivered downwardly as indicated in Fig. 2. Portions of the delivery mechanism are indicated at 81. This mechanism forms the 45 subject matter of my concurrently filed application for Paper delivery mechanism, Serial No. 703,099 filed December 19, 1933.

The structure above set forth is that which 50 normally operates during the use of the machine, so long as the paper is taken from the active web.

Web replenishing mechanism

The upper rear part of the side frames 20 and 21 carry a shaft indicated at 100. Transfer 55 cams 101 and 102 are pinned to this shaft and carried outside the side frames and a transfer cam operating arm 103 is adapted to bear on the active web roll W. The shaft 100 is biased in a clockwise direction by a coiled spring 104 connected to an arm 105 secured to the shaft 100.

It will thus be seen that the position of the transfer cams 101 and 102 will depend upon the amount of paper remaining on the active roll W. The lower ends of these transfer cams are flanged outwardly as indicated at 106 and 107 and are arcuate about the center of the shaft 100, as indicated. The extent of the clockwise movement of the shaft 100 is limited by a stop member 70 108 formed out of the side frame.

Transfer levers 110 and 111 are slotted, as indicated at 112, and received over the studs 40a and 41a, respectively. The rear ends of these transfer levers are bent laterally, as indicated at 75

113 and 114, so as to engage with the lower ends of the transfer cams 101 and 102.

The front ends 115 and 116 of the transfer arms are bent laterally and secured to a tie bar 5 117 by screws 117'. They also carry a shaft 118. The shaft 118 carries a blade 119 urged in a clockwise direction by coiled spring 120. It is held in the position indicated in full lines in Fig. 4 by engagement with a stop indicated at 10 121. The front ends of the transfer levers 110 and 111 also carry a clamp plate 122 pivotally secured as indicated at 123. This plate is adapted to rest by gravity on the upper edge of the tie plate 117, as indicated more clearly in Fig. 4.

15 The reserve web roll is indicated at R. It is a roll identical with roll W and is supported in bearing members indicated at 124, similar to the bearing members 72. Arms 125 are provided with friction shoes 126 and are pressed against 20 the paper roll ends 127 by springs 128 in the same way that the active web roll is held. The reserve web r is passed underneath the plate 119. It is then carried forward above the tie plate 117 and when the clamping plate 122 is turned 25 to the dot and dash position of Fig. 2, is doubled back on itself, somewhat as shown in Fig. 4. The clamp plate 122 is then returned to the full line position of Figs. 2, 3, and 4 so that it bears on the doubly folded paper.

30 When the active web roll W is depleted sufficiently, the transfer cam operating arm 103 is moved into the dotted line position of Fig. 3, whereupon the cams 101 and 102 are moved forward to clear the lateral extensions 113 and 114 35 on the transfer arms 110 and 111. This allows the heavy mechanism carried on the front ends of these transfer arms to lower from the full line position to the dot and dash line position of Fig. 3. They are supported by engagement of the tie bar 117 with the portion 129 of the side frames 20 and 21. When this happens the blade 119 passes between the upper surface of the female roller 28 and the lower surface of the active web w, the blade 119 being swung counter-clockwise 40 to a slight extent against the tension of the spring 120. When the rollers are now turned to continue to draw the active web w into the machine, the friction between the reserve web r and the active web and drawing roller is sufficiently 45 great to pull the paper out from under the clamp plate 122 (if it has not already been pulled free), whereupon the reserve web r is carried on through the machine in the same way as the active web w. The machine can then continue to 50 be operated as long as desired, or until the reserve roll is exhausted. Before this time, however, the attendant should have serviced the machine.

55 The indication of the fact that the active roll has been exhausted is given by the signal carrying member 130, secured to the right transfer arm and visible through an opening, not shown in the front of the case.

To pass the web roll from the upper set of 60 bearings to the lower set of bearings, it is merely necessary to open the case, remove the core of the spent roll, pull the roll R with roll ends out of the upper bearings, and bodily shift it down into the lower bearings while the transfer arms have been lifted. This will shift the transfer cam 65 shaft to the normal position so that the transfer arms will be supported in the elevated position ready for the insertion of the new reserve roll.

70 The first time that the machine is threaded, it 75 is desirable to have the blade 119 and associated

parts out of the way or in an elevated position, such as indicated in Fig. 2. This may readily be accomplished by lifting these parts upwardly and pulling them forward against the tension of springs 131. The slots 112 allow this forward 5 movement so that the parts can be passed up about the upper ends of the arms 125, as indicated by the row of dots 132, Fig. 2. When the parts are thus elevated, the roll may be readily moved into the bearings and one can manually 10 pass the paper down between the guide roll and the female roller and work it into the machine.

In the arrangement shown in Fig. 5, the upper rear part of the right hand frame is shown at 150, and the lower front part of the left hand frame is shown at 151. The first drawing roller 153 may correspond with the female roller 28 of Figs. 1-4, while the cooperative drawing roller is indicated at 154 and the delivery roller at 155. These rollers are geared together in the usual 20 manner and operated by a crank as previously described. The male roll and controls for it are omitted from this figure.

The active web roll W' and reserve web roll R' 25 are carried in suitable bearings in the frames 150 and 151, and the active web w' passed about a guide roll 156 as before. A weighted drag bar 157 bears on the roll W' and approaches the roll axis as the paper is unwound.

An arm 158 is secured to a rock shaft 159 and has its free end in the path of the drag bar. The shaft 159 carries a cam arm 161 on the outside face of the frame 150 and the arms 158 and 161 and shaft 159 are pulled counter-clockwise by a coiled spring 162, secured to the frame 150 and to a pin 163. The pin acts as a stop to hold these parts normally in the full line position shown. When the active roll is exhausted these parts are moved to the dot and dash line position.

Transfer levers 164 and 165 are pivoted at 166 30 to the frames and are secured together by a tie bar 167 similar to the tie bar 117. The arms are held in the full line position by a lug 168 which engages the upper face of arm 161. The transfer arms carry a shaft 169 about which is pivotally mounted a paper inserting blade 170, and also a clamp plate 171 pivoted at 172. The blade 170 is provided with a finger 173 which extends 40 downwardly as indicated, and is pressed downwardly by a spring similar to the spring 120. 45

The reserve web r' is secured about the blade 170 and under the clamp plate 171 in the same manner as previously described. When the drag bar moves the bell crank 158-161 to the dot and dash line position, the arm 161 passes beyond the lug 168 and allows the transfer arms to drop to the dot and dash line position shown. The blade presses the reserve web against the roller 153, from which position it will be drawn into the machine in the same way as previously described.

50 As here shown this roller is provided with a pin 174 which engages the extension 173 of the blade and pushes the blade further to the right, the arms dropping lower. The axis of the blade supporting shaft 169 is now at the point marked 169' and the paper forced into the narrow space between web w' and roller 173. The reserve web r' 55 is now used, the drag bar 157 keeping it taut.

The drag bars 157 and 155 and the transfer arms 60 may be swung up and back to be out of the way when necessary during servicing of the machine.

65 It is obvious that the invention may be embodied in many forms and constructions within the scope of the claims, and I wish it to be under- 70

- stood that the particular forms shown are but two of the many forms. Various modifications and changes being possible, I do not otherwise limit myself in any way with respect thereto.
5. What is claimed is:
1. In web handling mechanism, in combination, means for supporting an active web roll and a reserve web roll, web drawing means including rollers between which the active web is passed to pull the active web off the active web roll, whereby said active web roll is depleted, means for applying the web to the first of said rollers so that the web contacts with an extended surface of said roller, and means responsive to such depletion of the active web roll below a predetermined size for inserting the end of the reserve web between the active web and the roller to which it is applied, so that the reserve web is frictionally gripped therebetween and carried between the drawing means, said web inserting means including a movable support which releasably holds the free end of the reserve web in position for such insertion.
  2. A web handling mechanism such as claimed in claim 1, having means for holding the movable support in fixed position throughout the depletion of the active roll until said predetermined diameter is reached, whereupon the movable support is released.
  3. A web handling mechanism such as claimed in claim 1, wherein the movable support includes a blade about the edge of which the end of the reserve web is folded, the blade being movable tangentially of the first roller when the web is being inserted.
  4. A web handling mechanism such as claimed in claim 1, wherein the movable support includes a blade bodily movable tangentially of the first roller, about which the free end of the reserve web is folded, and a pivot for the blade to permit its edge to move radially of said roller.
  5. A web handling mechanism such as claimed in claim 1, wherein the means for holding the end of the reserve web on the movable support is in the form of a gravity operated clamping bar bodily movable with the support.
  6. In web handling mechanism, in combination, means for supporting an active web roll and a reserve web roll, web drawing means including rollers between which the active web is passed to pull the active web off the active web roll, whereby said active web roll is depleted, means for applying the web to the first of said rollers so that the web contacts with an extended surface of said roller, and means responsive to such depletion of the active web roll below a predetermined size for inserting the end of the reserve web between the active web and the roller to which it is applied, said inserting mechanism including a gravity actuated member to which the end of the reserve web is detachably secured, and means to hold the gravity actuated member in elevated position until the active roll depletion is accomplished.
  7. In web handling mechanism, in combination, means for supporting an active web roll and a reserve web roll, web drawing means including rollers between which the active web is passed to pull the active web off the active web roll, whereby said active web roll is depleted, means for applying the web to the first of said rollers so that the web contacts with an extended surface of said roller, and means responsive to such depletion of the active web roll be-
  - low a predetermined size for inserting the end of the reserve web between the active web and the roller to which it is applied, said inserting mechanism including a releasably supported member disposed parallel of the axis of the first roller and held adjacent said roller during the depletion of the active web roll and released upon the depletion of the active web roll, the end of the reserve web being folded about the edge of said member and releasably secured thereto so as to move with the member when released.
  8. In web handling mechanism, in combination, means for supporting an active web roll and a reserve web roll, web drawing means including rollers between which the active web is passed to pull the active web off the active web roll, whereby said active web roll is depleted, means for applying the web to the first of said rollers so that the web contacts with an extended surface of said roller, and means responsive to such depletion of the active web roll below a predetermined size for inserting the end of the reserve web between the active web and the roller to which it is applied, said means including a follower bearing on the active web roll and movable as the web is removed, a lever engageable with the follower and held stationary until the depletion is accomplished, and a web inserting blade carried by the lever for holding the reserve web out of contact with the first roller until the lever is released.
  9. In a web handling mechanism, in combination, means for supporting an active web roll, and a reserve web roll, web drawing means including rollers between which the active web is passed to pull the active web off the active web roll whereby said active web roll is depleted, means for applying the web to the first of said rollers, so that the web is in contact with an extended surface of the said roller, a follower positioned according to the diameter of the active web roll, a transfer arm held by the follower in a fixed position so long as the diameter of the active roll exceeds a predetermined size and released when that size is reached, a web inserting blade carried by the transfer arm between the active web and adjacent surface of said first roller and movable when the arm is released to bring its free edge toward the point of application of the active web to the first roller, and a clamp moving with the blade and adapted to releasably secure the reserve web about the blade so that the blade when released will push the reserve web against the active web and roller to be drawn away from the clamp and carried between the active web and roller.
  10. Web handling mechanism such as claimed in claim 9, wherein the blade is pivoted on a longitudinal axis and under the control of a spring which, when the transfer arm is released, presses the edge of the blade toward said first roller.
  11. In a web handling mechanism, in combination, side frames adapted to detachably support an active web roll and a reserve web roll, web drawing means including rollers revolvably supported by the side frames and through which the active web is passed, whereby said active web is depleted, a guide to apply the web to the first roller, a blade between the guide and the first roller and movable toward and away from the point of application of the web to said roller, and means to secure the end of the reserve web to the blade, means to hold the blade away from the first roller, and means acting to release the blade

upon depletion of the active roll beyond a predetermined amount so that the end of the reserve roll is inserted in between the active web and the first roller.

5 12. In a web handling mechanism, in combination, side frames adapted to detachably support an active web roll and a reserve web roll, web drawing means including rollers revolvably supported by the side frames below the reserve and active web rolls and through which the active web is passed, whereby said active web is depleted, a guide above the first roller to apply the web to the first roller, a blade between the guide and the first roller and movable toward and away from the point of application of the web to said roller, and means to secure the end of the reserve web to the blade, means to hold the blade away from the first roller, and means acting to release the blade upon depletion of the active roll beyond a predetermined amount so that it drops down under the influence of gravity and the end of the reserve roll is inserted in between the active web and the first roller.

10 13. A web handling mechanism adapted to employ an active web roll and a reserve web roll and having web drawing means including rollers between which the active web is passed, a guide for applying material from the active web roll to the first roller, whereby the active web is in contact with said roller about an extended surface thereof, and means for inserting the reserve web between the first web and said roller comprising a blade having means for releasably holding the end of the reserve web thereto, means for holding the blade in position so that the reserve web is out of contact with the first web and roller, and means for moving the blade into such position that the reserve web frictionally engages both the first web and the roller, so that the reserve web is pulled off the blade and carried in between the first web and said roller.

15 14. A web handling mechanism adapted to employ an active web roll and a reserve web roll and having web drawing means including rollers between which the active web is passed, a guide for applying material from the active web roll to the first roller, whereby the active web is in contact with said roller about an extended surface thereof, and means for inserting the reserve web between the first web and said roller comprising a blade having means for releasably holding the end of the reserve web thereto, means under the control of the active web roll for holding the blade in position so that the reserve web is out of contact with the first web and roller so long as the size of the active web roll exceeds a predetermined size, and means for moving the blade into such position that the reserve web frictionally engages both the first web and the roller so that the reserve web is pulled off the blade and carried in between the first web and said roller.

20 15. A web handling mechanism adapted to employ an active web roll and a reserve web roll and having web drawing means including rollers between which the active web is passed, a guide for applying material from the active web roll to the first roller, whereby the active web is in contact with said roller about an extended surface thereof, and means for inserting the reserve web between the first web and said roller comprising a blade having a free edge about which the end of the reserve web is folded, a gravity operated

clamp bar under which the end of the reserve web is inserted, means for holding the blade in position so that the reserve web is out of contact with the first web and roller, and means for moving the blade into such position that the reserve web frictionally engages both the first web and the roller so that the reserve web is pulled off the blade and carried in between the first web and said roller.

25 16. In a web handling mechanism, a horizontal drawing roll, a second drawing roll, a guide roll above the first drawing roll, means to revolvably support an active web roll, the active web being passed about the guide roll and first drawing roll and then between the two drawing rolls so that turning the drawing rolls withdraws the active web, a web inserting blade, normally stationary, pivotally supported arms for supporting the blade adjacent the guide roll, means for releasing the arms so that they swing downwardly and pass the edge of the blade between the first drawing roll and guide roll, whereby the end of a reserve web detachably secured to the blade may be pushed in between the active web and first drawing roll.

30 17. In a web handling mechanism, a rotatable roller, an adjacent guide roller spaced slightly from the rotatable roller for applying a web to the rotatable roller, and a web inserting blade normally held in fixed position adjacent both rollers and adapted to releasably carry a reserve web, and means to move the blade into the space between the two rollers whereby the reserve web is pushed between the rotatable roller and first web.

35 18. In a web replenishing mechanism, a roller about which an active web may be partially wrapped, a blade parallel with the roller, means to hold the blade out of contact with the roller or the active web, a clamp parallel with the blade and bodily movable therewith, the clamp being adapted to secure the end of a reserve web which has been carried about the free edge of the blade, and means to guide the blade upon its release to move the reserve web into contact with the active web and roller.

40 19. A web replenishing mechanism as claimed in claim 18, having a spring tensioned when the blade with the reserve web is brought against the roll.

45 20. In paper handling, the method of feeding a reserve web into a machine having drawing rolls between which an active web has previously been inserted, which consists in placing the end of the reserve web into frictional contact with the active web and the drawing roll about which the active web first passes so that the reserve web is gripped therebetween and carried into the machine between the active web and said roll.

50 21. In paper handling, the method of feeding a reserve web into a machine having drawing rolls between which an active web has previously been inserted, which consists in first folding the reserve web along a transverse line near the end thereof to form a straight transverse edge of double thickness, and then applying pressure to the folded web from the inside of the fold so that the entire width of the folded web is brought into frictional contact with the active web and first drawing roll and the reserve web is pulled thereby in between said active web and roll.

55 22. In a web handling mechanism, a frame, bearings for supporting an active web roll in a horizontal position, a spring pressed shoe bearing on the web roll and movable inwardly as the

roll is depleted, a cam member movable with the shoe, a pivotally supported transfer arm having its rear end bearing on the cam and held stationary thereby until the diameter of the active roll is reduced to a predetermined size, whereupon the transfer arm is released, a blade carried by the

front end of the transfer arm about which a reserve web is adapted to be folded, and a gravity operated clamping member for engaging the end of the web after it is folded about the edge of the blade.

GEORGE SCHAEFER, JR.
